US0D1028049S

(12) **United States Design Patent** (10) Patent No.: **US D1,028,049 S**
(45) Date of Patent: ** May 21, 2024

(54) **EYEGGLASS CASE**

(71) Applicant: **HUAWEI TECHNOLOGIES CO., LTD.**, Guangdong (CN)

(72) Inventors: **Zengzhu Deng**, Shenzhen (CN); **Jie Huang**, Shanghai (CN)

(73) Assignee: **HUAWEI TECHNOLOGIES CO., LTD.**, Shenzhen (CN)

(**) Term: **15 Years**

(21) Appl. No.: **29/822,769**

(22) Filed: **Jan. 12, 2022**

(30) **Foreign Application Priority Data**

Jul. 13, 2021 (CN) 202130443505.6

(51) LOC (14) Cl. **13-02**

(52) U.S. Cl.

USPC **D16/100**

(57) **CLAIM**

The ornamental design for an eyeglass case, as shown and described.

DESCRIPTION

FIG. 1 is a front perspective view of an eyeglass case, showing our new design;

FIG. 2 is a front view thereof;

FIG. 3 is a back view thereof;

FIG. 4 is a top view thereof;

FIG. 5 is a bottom view thereof;

FIG. 6 is a left side view thereof;

FIG. 7 is a right side view thereof; and,

FIG. 8 is a back perspective view thereof.

The broken lines in drawings show portions of the eyeglass case that form no part of the claimed design.

1 Claim, 6 Drawing Sheets
